UNITED STATES PATENT OFFICE.

ORREN I. SEARLES, OF JOPLIN, MISSOURI.

MUSIC-LEAF TURNER.

1,071,470.

Specification of Letters Patent. Patented Aug. 26, 1913.

Application filed August 3, 1912. Serial No. 713,163.

To all whom it may concern:

Be it known that I, ORREN I. SEARLES, a citizen of the United States, residing at Joplin, in the county of Jasper and State of Missouri, have invented certain new and useful Improvements in Music-Leaf Turners, of which the following is a specification, reference being had to the accompanying drawings.

10 This invention relates to new and useful improvements in music leaf turners, the object of the invention being to provide a device of this character for holding and turning the leaves of sheet music and thus relieving the operator from the necessity of actually taking hold of the leaf when it is required to be turned.

Another object of the invention is to provide a device of this character which will 20 possess advantages in points of efficiency and durability, is inexpensive to manufacture and at the same time is simple in construction and operation.

With the above and other objects in view, 25 the invention consists in the novel features of construction and the combination and arrangement of parts hereinafter more fully described, pointed out in the claims and shown in the accompanying drawings in 30 which—

Figure 1 is a front elevation, the arms being shown in their operative position. Fig. 2 is a similar view showing the arms in their inoperative position. Fig. 3 is a sectional view on the line 3—3 of Fig. 1. Fig. 4 is a sectional view on the line 4—4 of Fig. 2. Fig. 5 is a detail perspective view of one of the pivoted arms. Fig. 6 is a detail perspective view of the second pivoted arm and 40 Fig. 7 is a sectional view on the line 7—7 of Fig. 3.

Referring more particularly to the drawings, 1 indicates the base or back of the turner and upon which is mounted a suitable 45 housing 2. Secured to the base 1 and arranged at the lower end of the housing is a U shaped member 3 which is provided at one end with the upwardly extending ears 4 in which is mounted a suitable shaft 5.

50 Pivottally mounted at one of their ends upon the shaft 5 are the leaf turning arms 6 and 7, the arm 6 being provided with an angular extending portion 8 having the spaced ears 9 formed upon the end thereof whereby the 55 arm is pivottally mounted upon the shaft 5. The other ends of the arms 6 and 7 are piv-

otally mounted upon the upwardly extending flange 10 which is bent at right angles to the upper end of the base 1.

The lower ends of the arms 6 and 7 are 60 provided with the angular extensions 11 having elongated slots 12 formed therein which are adapted to receive the pivottally mounted catch members 13 so as to hold the arms in an operative position, these catch 65 members 13 are pivottally mounted upon the cross rods 14 mounted in the side walls of the U shaped member 3. The catch members 13 are provided with the angular extensions 15 which are bifurcated to form the 70 recesses 16 in which are disposed the operating rods 17, said rods being operatively mounted in the slots 18 formed in the U shaped member 3 and the inner ends of said rods being suitably secured to the cross piece 75 19 upon the base 1 while the intermediate portion of the rods is arranged across a supporting member 20 which normally holds the outer ends of the rods in one end of the slots 18 so that when the catch members 13 80 are engaged in the slots 12 pressure upon the finger pieces 21 at the outer ends of the rods will release the arms.

Mounted upon the shaft 5 and arranged between the ears 9 and 9' are the coil springs 85 22, said springs each having one of their ends engaging the lower ends of the arms 6 and 7 and the other ends of said springs being suitably secured to one of the rods 14, so that when the arms are swung to an 90 operative position, the springs will be placed under tension, the tension of said springs returning the arms to their normal position when the catch members 13 are released. The upper ends of the arms 6 and 7 are provided with an enlargement 23 which is slit 95 upwardly at its lower end as shown at 24 to form the elongated portions 25 which are spaced from the arms and arranged in parallel relation therewith. The enlarged 100 portions 23 are provided upon their outer edge with an outwardly extending flange 26 which is cut away at its lower end as shown at 27 and the end of the elongated extensions 25 are bent outwardly as shown 105 at 28 to form suitable catches with which the pivoted fingers 29 are engaged to hold them in a substantially horizontal position with respect to the arms 6 and 7. In order to release the fingers 29 from the catches, 110 the lower end of the elongated extensions 25 is pressed toward the base of the turner

until the pivoted leaf will pass beyond the outwardly turned portion 28 whereby the finger may then be arranged in parallel relation with the arms. The upper longitudinal edges of the fingers 29 are provided with an overturned edge forming a channel 30 adapted to hold the music. A third pivoted finger 31 is pivotally secured to the base 1 as shown at 32 and adapted to be disposed 10 in a horizontal position with respect to the base. This finger is provided upon its upper edge with a suitable clip 33 adapted to engage over the upper edge of the cover of the music to hold the same in place and to further hold the music spring catches 34 are secured to the outer ends of the fingers 29 and 31 and adapted to engage over the music. Spring catches 35 are arranged at the upper and lower ends of the arms 6 and 20 7 and at the outer end of the fingers 29 to engage the various leaves of the music to hold the same in place. One of the longitudinal edges of the arm 7 is provided with an extension which is adapted to be curved 25 inwardly upon the arm to form a suitable channel 36 adapted to receive the inner edge of the free leaf of the music so as to prevent the leaf from catching on the lower leaf when the arm is turned, this channel 36 may 30 also be used as a guide in inserting the music.

From the above description taken in connection with the accompanying drawings it will be readily apparent that I have provided a simple and durable music leaf turner whereby the leaves of the music may be quickly and readily turned by the simple exertion of pressure upon the ends 21 of the arms 17, thus releasing the catch members 35 40 13 from the slots 12 allowing the arms 6 and 7 to turn through the tension of the springs 23.

While I have shown and described the preferred form of my invention it will be obvious that various changes in the details of construction and in the proportions may be resorted to for successfully carrying my invention into practice without sacrificing any of the novel features of construction or 45 departing from the scope of the appended claims.

What I claim is:—

1. In a device of the character described, the combination of a base, leaf turning arms pivotally mounted upon said base for relative swinging movement and spring pressed in one direction, means for holding said arms relatively stationary with their springs under tension, means for releasing said holding means, pivoted fingers at one end of said arms and normally arranged in a horizontal position, enlarged portions formed at one end of said arms, elongated extensions formed on said enlarged portions spaced from and arranged in parallel relation with the arms and resilient catches formed on said extensions and adapted to engage the fingers to hold them in a normal horizontal position.

2. In a device of the character described, the combination of a base, leaf turning arms pivotally mounted upon said base for relative movement and spring pressed in one direction, said arms being provided at one end with transverse slots, pivoted catch members mounted on the base and adapted to be disposed in said slots to engage the arms and hold the same relatively stationary with their springs under tension, means for releasing said catch members, pivoted fingers at one end of said arms and arranged in a horizontal position, enlarged portions formed at one end of said arms, elongated extensions formed on said enlarged portions, spaced from and arranged in parallel relation with the arms, catches formed on the ends of said extensions and adapted to engage the fingers to hold them in a horizontal position, the upper longitudinal edges of said fingers being provided with an overturned edge to form a channel and one of the longitudinal edges of one of said arms being provided with an extension which is adapted to be curved inwardly upon the arm to form a channel.

In testimony whereof I hereunto affix my signature in the presence of two witnesses.

ORREN I. SEARLES.
